UNITED STATES PATENT OFFICE.

WARD BUTLER, OF CHICAGO, ILLINOIS.

BOMB-THROWING MACHINE.

1,344,378.

Specification of Letters Patent. Patented June 22, 1920.

Application filed August 24, 1918. Serial No. 251,227.

To all whom it may concern:

Be it known that I, WARD BUTLER, a citizen of the United States, residing in Chicago, in the county of Cook and State of Illinois, have invented a new and useful Improvement in Bomb-Throwing Machines, of which the following is a specification.

This invention relates in general to throwing machines and has more particular reference to a throwing machine provided for use in trench warfare for the throwing of hand grenades, bombs and the like.

The invention has for its principal object the provision of a simple, accurate and effective throwing machine adapted for the purpose above specified. The purpose of the invention is therefore to provide a throwing machine of compact form, the parts of which will be so constructed and arranged that the throwing of the missile may be accomplished with the machine and its operators located beneath the top of the trench and so without exposing the operators or machines to the fire of the enemy.

A further and highly important object of the invention is the provision of such a machine which will not require substantial enlargement or deepening of the trenches for its use and which can be operated without requiring the provision of a specially constructed base or support.

Another highly important object of the invention is the provision of a machine of this character, which may be operated by a single man and which will be readily and accurately controllable as to elevation and distances.

Another object of the invention is the provision of a machine of this character so constructed that it may be collapsed and thus require little space in storing and transit and also capable of being easily moved about when in fully extended or operative condition, and this by no more than two men and in emergency by a single man.

Another and extremely important object of the invention is the provision of a throwing machine of the character and for the purpose mentioned, which may be of such simple and cheap construction that it may be provided in great quantities at low cost.

A still further object is the provision of such a construction which may be rendered inoperative by the removal of a small part which is not readily replaceable.

Numerous other objects and advantages

of the invention will be apparent as it is better understood from the following description when considered in connection with the accompanying drawing illustrating a preferred embodiment thereof.

On the drawing,

Figure 1 is a side elevation of a throwing machine embodying my present invention showing the parts arranged in normal position;

Fig. 2 is a similar view showing the arrangement of the parts after throwing;

Fig. 3 is a top plan view of the same showing the parts as arranged in Fig. 1;

Fig. 4 is a back elevation of the same;

Fig. 5 is an enlarged detail view shown partially in section and illustrating the construction of the drums and the connections to them of the throwing arm;

Fig. 6 is a partial enlarged sectional view taken along the shaft of the throwing arm;

Figs. 7 and 8 are respectively side and front elevations of the crank and latch mechanism provided for storing power in the throwing springs; and

Fig. 9 is an enlarged detail section taken substantially on the line 9—9 of Fig. 1.

For the purpose of illustrating my invention, I have shown on the drawings an angle iron frame work of skeleton form. This frame is made collapsible and consists of a skeleton framework of boxlike form.

Each side rectangular part consists of a base composed of bottom members 11 and 13 hinged together at 12. The bottom member 11 is pivoted at 15 with a lower back member and the member 13 is fixed to a lower front member.

The front member comprises an upper main member 16 and a lower member 10 pivoted together at 20. The back member at each side consists of detachable connected angle iron parts 17 and 18 which may be secured together by a thumb nut 19.

The top of each side frame consists of top members 21 and 22 similar to the back members 17 and 18 and similarly connected by thumb nut 23. At the front the side member 16 is pivotally connected at 24 with the member 21.

At each side also a cross bracing strut of angle iron 25 is rigidly connected with the member 18 at the top and the member 13 at the bottom. The members 10 and 13 are rigidly connected together and an angle iron 26 extends across to rigidly connect the two sides of the frame together at the front.

A plate 27 connects the two members 16 rigidly together and the members 17 are connected by the hinge 15. The members 18 and 22 are rigidly connected together by 5 bearings 29 for a throwing shaft 31. The frame may be collapsed and the working parts inclosed by removing the thumb nuts 19 and 23 folding in the members 17 and 21 upon the members 11 and 16 and then 10 folding these members upon the struts 25 bringing the entire frame and the parts carried by it to compact arrangement.

Upon the shaft 31 is mounted a throwing arm 32 carrying at its free end a throwing cup or grenade receiving pocket 33. This arm in the present instance is connected, as will be seen in Fig. 5, to the shaft 31 through the medium of two drums 34 which are fixed upon the shaft by swaging 20 or other suitable connection. Each drum 34 consists of a pair of disks 35 connected by rivets 36, the disks being spaced apart by rollers or sleeves 37 one upon each rivet. Two angle irons 38 are extended between 25 the drums and engage fasteners 39 for holding the throwing arm in place. A flexible member or chain 41 is disposed over each drum and held against slipping thereon by a pin 42 disposed through the two plates 30 35 of the drum and through the chain. One end 43 of the chain is connected to a throwing motor or spring 44 which in turn is connected at its other end with a pulley 45. A chain 46 connected at 47 with the appropriate member 13 takes over pulley 45 35 under a pulley 48 carried upon the member 26 and up over a winding drum 49.

The swinging arm when in normal position, as shown in Fig. 1, is disposed with 40 the cup resting upon a latch support which is in form of a platform 51 on a pivot shaft 50 and held up by latches 52 which have tails 53 connected by links 54 to arms 55 upon a shaft 56 pivoted in the member 16, 45 one or both of the arms 55 providing a release handle. Fig. 1 shows the arrangement of the parts in this normal position and the arrangement of the spring 44 before the tension is placed in it. This tension is provided by winding up the chains 46 on the drum 49. This drum is fixed upon a shaft 61 which is rotatable in suitable bearings 62 in the front of the frame. Shaft 61 has fast upon it at one end a ratchet wheel 63 and loose upon it a crank arm 64. This 50 crank arm carries a pawl 65 slidably mounted in bearing lugs 66 and pressed by a spring 67 toward the ratchet wheel. The outer end 68 of the pawl 65 is bent over 55 to form a finger piece for releasing the pawl and this extends through a slot 69 of the crank 64 in the present instance.

A locking detent 71 pivoted at 72 on the frame is pulled by a spring 73 into engage-

ment with the ratchet wheel. When the 65 parts are arranged as shown in Fig. 1 the crank arm 64 is given two or three turns in a clockwise direction, pulling down upon the end of the spring 44, elongating it and storing up the throwing power. After this 70 power is stored up the latch support holding up the throwing arm is tripped and the arm swings downwardly and out at the rear and then forwardly and upwardly in a 75 throwing movement, which movement in the present instance is considerably over 180°. The missile is caused to leave the throwing arm by the engagement of a cross bar 74 carried by arms 75 of levers consisting of these arms and of longer arms 76 and pivoted upon the shaft 31. Motor springs 77 are attached at 78 on the arms 76 and at 79 on the frame members 21, which springs tend to move the bar 74 in a counterclockwise direction. This movement is limited 80 by chains or other flexible members 81 secured at 82 to the lower ends of the arms 76 and taking around pulleys 83 on the frame. The other ends of the chains or flexible members 81 are connected to an adjustable slide member 84 (Fig. 9) having oppositely extending fingers or pins 85 which take into holes 86 in the base members 11, the adjustment of this block determining the point of engagement between the bar 74 and the swinging arm for the purpose of accurately adjusting the point of discharge of the missile. After engagement by the bar 74 with the throwing arm the force of the spring 77 immediately produces a slowing movement of the throwing arm causing the missile to leave it with its 90 acquired momentum.

It will be manifest that adjustment of the block 84 provides for the determination of 105 the elevation given to the missile at its time of discharge, and the amount of winding given the sleeve or drum 49 determines the amount of momentum or the distance that the missile will travel at any particular elevation. Moreover the elevation or the force can be independently altered so that any 110 combination of distances and height within the range of the machine is attainable.

In order to enable the operator to accurately repeat a shot or to alter the shot a predetermined amount, I provide a scale 91 upon the strut 25 and the lower end of the spring 44 is brought opposite a desired graduation upon successive actions or beyond 115 a graduation previously selected a predetermined amount for correction of distance.

Return springs 92 are fixed at 93 to the frame members 12 and also to the ends 94 of the chains 41 beyond the drums 34. The 120 springs 92 are materially weaker than the springs 44 and when the throwing arm is released and the drums 34 rotated in a clock-

wise direction (viewing Sheet 1 of the drawings) the portions of the chains connected to the springs 92 wind up on the drums 34 extending the springs. If now the tension 5 sleeve 49 be released, the springs 92 will contract moving the arm back in a counter-clockwise direction to reloading or normal position. Release of the sleeve 49 is accomplished by a pull upon the finger piece 68 of 10 the pawl 65. This pawl carries with it an offset L-shaped finger member 95 engageable behind a pin 90 on the detent 71 when the finger piece 68 is pulled down so that this 15 detent as well as the pawl itself is withdrawn upon manipulation of the finger 68.

If the pin 42 or the throwing arm be removed, and either of these parts may be easily arranged for ready removal, the device is inoperative, and this manipulation 20 may be resorted to if abandonment of the machine becomes necessary.

I have found that an apparatus embodying my invention can be easily loaded and discharged at the rate of 60 or more a minute 25 and it will be manifest that it is light and durable and can easily be carried about either collapsed and in large numbers or extended and singly by the operators. The strut 25 lying close and parallel to the application of the throwing force is all the reinforcement necessary and the location of the bearings 29 is such that they take up the severe throwing strain along the lines of the frame best calculated to resist these strains. 30 The space required for the machine in the trench need not be more than six feet in width and of any ordinary trench depth. A couple of boards is all that is necessary to form a base in muddy ground and even these 35 are unnecessary where the ground is solid.

It is thought that the invention and many of its attendant advantages will be understood from the foregoing description, and it will be apparent that various changes may 40 be made in the form, construction and arrangement of the parts without departing from the spirit and scope of the invention or sacrificing all of its material advantages, the 45

form hereinbefore described being merely a preferred embodiment thereof.

50

I claim:

1. A throwing machine, comprising a throwing arm, a return motor and a throwing motor, said throwing motor propelling the throwing arm in throwing and storing 55 the power in the return motor for returning said throwing arm to normal position.

2. In a throwing machine, the combination of a throwing arm, a drum rotatable with said throwing arm, a flexible member 60 taking over said arm, return, and throwing motors engaging the ends of said flexible member.

3. A throwing machine, comprising in combination a throwing arm, a throwing 65 spring, a return spring, and a control, the return spring being controlled by said control through the throwing spring.

4. A throwing machine, comprising in combination a throwing arm, a flexible member 70 for moving said arm about its axis in throwing, a throwing spring connected to one end of said flexible member, a return spring connected to the other end, and a control for elongating said spring and holding 75 its advanced end during throwing and releasing the return spring for moving said arm and said throwing spring back to normal positions when said control is released.

5. A throwing machine, comprising a 80 throwing arm, a throwing spring adjustable as to tension prior to throwing, and a distance scale for determining the extension of said spring.

6. A throwing machine, comprising in 85 combination a throwing arm, a latch support for holding said throwing arm in normal position, a throwing spring, a return spring moving said throwing arm after throwing into position for engagement by 90 the latch support, and means for providing tension in said throwing spring after said throwing arm is engaged in said latch support.

WARD BUTLER.
